DAM

Calvin V. Davis, Mount Vernon, N. Y., assignor to
Amburseen Construction Company, Inc., New
York, N. Y., a corporation of New York

Application February 26, 1934, Serial No. 712,868

5 Claims. (Cl. 61—32)

This invention relates to a novel and improved dam, the novel features of which will be best understood from the following description and the annexed drawing, in which I have shown a selected embodiment of the invention, and in which:

Fig. 1 is a vertical sectional view on a plane extending up-stream and down-stream, and showing one form which the invention may take.

10 Fig. 2 is a section on the line 2—2 of Fig. 1. This invention relates to a form of dam sometimes referred to as the Amburseen type or, in other words, to a hollow dam, in which there is provided an inclined up-stream water-bearing deck supported by a plurality of buttresses extending down-stream from the deck. In the design of this type of dam, particularly on soft foundation material, it is sometimes difficult to provide the proper amount of safety against 20 sliding on the foundation material, and the difficulty is increased by the seepage of water under the dam which almost invariably takes place in any type of dam.

It has been common practice to make the slope 25 of the deck a flat one, in order to increase the amount of water bearing thereon and thus increase the weight exerted on the foundation. Of course, this arrangement will help resist sliding, but at the same time it necessitates a greater 30 amount of material in the deck and also in the buttresses, the buttresses not only being longer to take care of the longer deck, but also being made with more material to withstand the additional weight placed thereon by the additional 35 volume of water. Moreover, the arrangement being discussed results in an unfavorable distribution of principal stresses in the dam structure, particularly in the buttresses. This is particularly true with the second principal stresses 40 which should be in compression, but are actually apt to be in tension when following the prior art practice. The result is the necessity for use of steel reinforcement, particularly near the deck where its presence is undesirable.

45 According to this invention, I provide an inclined up-stream water-bearing deck 1 supported on buttresses 2, the down-stream edges of which may be joined by a wall 3, although this is not essential. It will be noted that the deck 1 is provided with a slope which is steep as compared 50 with generally accepted practice in this type of dam, particularly when the foundation material 4 is soft. This steepness of the deck slope makes it possible to decrease the material in the buttresses 2, both by decreasing the up-stream

and down-stream length thereof, and also by decreasing the amount of water carried by the deck and thereby making it possible to decrease the weight of the buttresses because of the relatively light load carried thereby.

Extending up-stream from the lower edge 5 of the deck is a slab 6 resting directly upon the foundation material 4 and preferably connected to the deck by a suitable expansion joint 7. The dam is provided with a suitable cut-off wall 8, 10 here shown as extending downwardly from the up-stream edge of the slab 6. Any water which seeps by or through the slab or cut-off wall may be collected in gravel pockets 9 and conducted by drains 10 into the spaces between buttresses. 15 The slab 6 is also preferably tied securely to the buttresses as by steel reinforcement 11.

By the above arrangement alone, the cost of the dam is materially reduced because of the great economy in material, for reasons fully described 20 above. At the same time, it will be seen that the sliding tendency of the dam is greatly reduced because of the weight of water acting upon the slab 6, but since this slab is resting directly upon the foundation material, no superstructure to 25 support the same is required. Similarly, the slope of the deck is such that the stresses in the dam are substantially all in compression, thus eliminating the necessity for reinforcing steel.

I have also shown a feature which may be used. 30 either alone or in connection with the slab 6 for decreasing the tendency for the dam to slide on the foundation material. Extending transversely into the buttresses and preferably connecting them, I provide a foundation 12 which is preferably arranged in one or more steps as indicated, with the rear edge 13 of each step lower than the front edge 14 thereof. On the rearmost step, the rear edge is connected to the lower edge of the deck or to the slab, in this case a suitable 35 joint 15 being indicated. The steps are preferably arranged substantially normal to the resultant forces acting in the buttresses and which may be represented by the arrows R₁ and R₂. By this arrangement, the resistance to sliding is greatly 40 increased, the tendency to slide being resisted, for example, by the material above the lines 15 and 16 acting, respectively, on the two steps of the foundation. It will be seen that the rear edge of the front step is higher than the rear edge of 45 the next up-stream step, so that a line 17 connecting them is inclined upwardly in a down-stream direction. This means that the general sliding movement of this dam would be along the 50 upwardly inclined plane in which this line is dis- 55

posed and therefore, of course, the tendency to slide is further diminished by the weight of the dam.

In order to avoid the building up of an uplift pressure caused by the percolation or seepage of water under the dam, the drains 10 have been provided, and I also provide drains 18 through the foundation 12. Water may then pass freely upwardly and run off in the space between buttresses, suitable drains 19 being provided through the down-stream wall 3, if such wall is used. Drains 20 may also be provided passing through the buttresses 2.

As a further feature of economy and safety, cross walls 21 may be provided extending between and connecting adjacent buttresses 2 and also connected to the foundation 12. These cross walls not only serve to stiffen and strengthen the superstructure as a whole, but also furnish an additional support for the foundation. For example, considering the foundation up-stream from one of the cross walls 21, it will be seen that this portion of the foundation has a four-way support in that it is supported on either side by adjacent buttresses and is supported at its down-stream edge by the cross wall and at its up-stream edge by the slab 6. When the cross walls 21 are used, suitable drains 22 may be provided therethrough, so that water discharged from the drains 10 and 18 may find its way to the drains 19.

While I have shown the invention as embodied in a specific form, it is to be understood that various changes in details may be made without departing from the scope of the invention, and I therefore do not intend to limit myself except by the appended claims.

I claim:

1. A dam comprising an inclined up-stream water-bearing deck supported by a plurality of spaced buttresses extending downstream therefrom, and masonry foundations for said buttresses extending transversely thereof, said foundations having one or more steps, with the up-

stream edge of a step disposed lower than the down-stream edge thereof.

2. A dam comprising an inclined up-stream water-bearing deck supported by a plurality of spaced buttresses extending down-stream therefrom, and masonry foundations for said buttresses extending transversely thereof and substantially closing the spaces between adjacent buttresses, said foundations having one or more steps, with the up-stream edge of a step disposed lower than the down-stream edge thereof.

3. A dam comprising an inclined up-stream water-bearing deck supported by a plurality of spaced buttresses extending down-stream therefrom, masonry foundations for said buttresses extending transversely thereof, said foundations having one or more steps, with the up-stream edge of a step disposed lower than the down-stream edge thereof, and bracing members extending between adjacent buttresses and connected to said foundation.

4. A dam comprising an inclined up-stream water-bearing deck supported by a plurality of spaced buttresses extending down-stream therefrom, masonry foundations for said buttresses extending transversely thereof, said foundations having one or more steps, with the up-stream edge of a step disposed lower than the down-stream edge thereof, and bracing members extending between adjacent buttresses and connected to said foundation at the down-stream edges of said steps.

5. A dam comprising an inclined up-stream water-bearing deck supported by a plurality of spaced buttresses extending down-stream therefrom, and masonry foundations for said buttresses extending transversely thereof, said foundations having one or more steps, with the up-stream edge of a step disposed lower than the down-stream edge thereof and with the lower edge of each step lower than that of the next step down-stream therefrom.

CALVIN V. DAVIS.
